MEANS FOR SHARPENING RAZOR BLADES

Charles B. Periolat, Chicago, Ill.

Application May 15, 1930. Serial No. 452,617

2 Claims. (Cl. 51—158)

This invention relates to means for sharpening razor blades, the object of the invention being to provide a simple, inexpensive and easily operated razor blade sharpening means whereby the blades of safety razors can be expeditiously and readily sharpened thereby to prolong the use of the blades, the principal object of the present improvement being to provide an improved sharpening means which will remove the feather edge 10 of the blade and thus prevent the blade from pulling during shaving and irritating the skin.

After a razor blade has been sharpened, what is known as the feather edge of the blade must be removed or otherwise during shaving it will 15 pull and irritate the face. Most of the sharpening devices commonly used merely sharpen the blade but do not remove the feather edge, consequently after a few shaves the blade is thrown away, but by removing the feather edge in a simple and expeditious manner, the life of the blade 20 is very materially prolonged. It is well known that the barber in sharpening his razor does this by honing the razor against the edge, thus removing the feather edge, while the manufacturers of the blade sharpens the blade exactly opposite and consequently the blade is received by the user with the feather edge unremoved and this feather edge is a rough edge. Consequently, 25 unless this edge is removed the blade has a tendency to pull and irritate the face. By means of the present improvement this feather edge is quickly and readily removed thus providing a keener edge and one that will not pull or irritate the face and thus the life of the blade is greatly increased.

30 In the drawing accompanying and forming a part of this specification:

Fig. 1 is a perspective view of this improved sharpening means.

Fig. 2 is a detail view of a razor blade, its holder 35 and intermediate shim.

Fig. 3 is a top view of the present improvement with the blade assembled in position to be sharpened.

Fig. 4 is a cross sectional view, taken on the 40 line 4—4 of Fig. 3.

Fig. 5 is an enlarged cross sectional view similar to Fig. 4, illustrating the manner of holding the device for sharpening the blade.

Fig. 6 is a perspective view of a somewhat different form of blade, shim and holder, and

Fig. 7 is a cross sectional view illustrating the manner of using the parts shown in Fig. 6.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawing, since the invention is capable of other embodiments, and that the phraseology which I employ is for the purpose of description and not of limitation.

This improved sharpening means in the form shown comprises a strop 2 which may be of rigid material and provided on one side with an edge sharpening material 3 and on the other side with an edge finishing material 4 which may be in the form of leather or other suitable material, whereby the blade may be sharpened on one face and finished on the opposite face of the strop. This strop is provided with a guide or guide-way 5 shown in the present instance as a slot, preferably located mid-way and longitudinally of the 60 strop. Located in this guide-way is a thumb piece or knob 6 shown made up of two parts 7 and 8 thread connected, whereby it may be readily positioned in the slot. In practice however, the knob or thumb piece may be made as an integral structure in which event it could be inserted into the slot by tilting the knob or one end of the slot would be formed circular to permit the ready insertion and withdrawal of the thumb piece which as hereinafter pointed out forms a 70 pressure gauge. The blade holder 9 in the present instance, shown in Fig. 2 comprises the usual blade holding portion of a well known safety razor having the three studs 10, 11 and 12 for projection into similarly located openings of a 75 blade 13. Located on the studs and between the blade and holder is a shim 14 having similar 80 openings to those in the blade.

In applying the blade 13 to the strop 2, it is located on the holder with the shim 14 therebetween, the center stud 11 being received by an opening 15 of the thumb piece or knob which acts as a gauge to flex or bend the blade to the shape of the holder when held in the hand in the manner shown in Fig. 5, the shim acting to 85 prevent the blade from bending too much and digging into the strop. The shim is made shorter than the blade to be stropped so that the blade can be readily removed without removing the shim and by means of the pressure gauge thumb 90 piece the edge of the blade will be raised into proper position to come in contact with the strop. Without this shim the gauge would so 100 flex the blade to conform to the concaved holder that the edges of the blade would dig into the 105 strop. 110

stropping surface. It will be obvious that the thickness of the shim will depend upon how high the cutting edge of the blade is to be raised to form perfect contact with the strop.

5 In practice, the usual handle of a safety razor can be used by screwing it on to the stud 11 so that this handle will thus act as a pressure gauge, but the present form of pressure gauge thumb piece is found preferable since it permits the 10 thumb to rest on top thereof and thus secure the proper pressure. In practice likewise, the stropping device could have a bevelled sharpening surface conforming to the edge of the blade and as heretofore stated the stropping device 15 could be formed of any suitable material.

When the form of blade, shown in Fig. 6, now being manufactured is to be stropped, it is merely necessary to change the shape of the shim to conform to the holder, such form of shim being 20 shown in said Fig. 6, whereby this new style of blade may be sharpened as easily as the old style.

By the present improvement it will be observed that by shifting the blade back and forth on the stropping surface under the proper pressure 25 exerted by the pressure gauge thumb piece and by means of the shim located between the blade and holder, the blade is flexed the proper amount properly to contact with the stropping surface and thus the blade is sharpened at right 30 angles to its edge, during the longitudinal movement of the blade relative to the strop and practical demonstration has shown that this improved device not only removes the feather edge, thus producing a better edge when the blade is 35 new, since the manufacturer usually sends out the blade without removing such feather edge, but the blade can be more efficiently resharpened with the result that in shaving no pulling of the hairs or irritation of the skin results.

40 It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A razor sharpening device comprising a sharpening strop having a lengthwise extending guide slot, a blade holder having means including a stud for positioning the blade, said holder constructed for use in shaving, means between the holder and blade for positioning the edges of the blade relative to the strop, a detachable handle slidable on the stud and shiftable in the guide slot and having a thumb engaging portion and co-operating with the blade holder to form gaging means whereby when the holder and handle are held between the thumb and finger, pressure on the blade will be regulated to prevent the digging in of the blade into the strop and also effective to hold the blade on the strop in position to sharpen the blade at right angles to its cutting edge during the shiftable movement of the handle lengthwise of the slot. 80

2. A razor sharpening device comprising a sharpening strop having a lengthwise extending guide slot, a blade holder having means including a stud for positioning the blade, said holder constructed for use in shaving, a shim between the holder and blade for positioning the edges of the blade relative to the strop, a detachable handle slidable on the stud and shiftable in the guide slot and having a thumb engaging portion and co-operating with the blade holder to form gaging means whereby when the holder and handle are held between the thumb and finger, pressure on the blade will be regulated to prevent the digging in of the blade into the strop and also effective to hold the blade on the strop in position to sharpen the blade at right angles to its cutting edge during the shiftable movement of the handle lengthwise of the slot. 95
